United States Patent Office

Des. 186,739
Patented Nov. 24, 1959

186,739

PORTABLE COOLER

Alfons Glassenhart and William J. Stolz, Phoenix, Ariz.

Application June 22, 1959, Serial No. 56,449

Term of patent 14 years

(Cl. D62—4)

Fig. 1

Fig. 2

Fig. 4

Fig. 3

Fig. 5

Fig. 1 is a perspective view of a portable cooler incorporating the design.

Fig. 2 is a plan view of the portable cooler shown in Fig. 1.

Fig. 3 is a front elevation of the portable cooler shown in Fig. 1.

Fig. 4 is a left hand side elevation of the portable cooler shown in Fig. 1, the right hand side elevation being substantially identical.

Fig. 5 is a rear elevation of the portable cooler shown in Fig. 1.

We claim:

The ornamental design for a portable cooler, as shown and described.
